CLAIM

The ornamental design for a I.V. pole clamp, as shown and described.

DESCRIPTION

FIG. 1 is a front perspective view of an I.V. pole clamp showing my new design;

FIG. 2 is an enlarged perspective view thereof;

FIG. 3 is an enlarged perspective view thereof, taken from the opposite side of FIG. 2;

FIG. 4 is a side elevational view thereof, the opposite side elevational view being a mirror image thereto;

FIG. 5 is a top plan view thereof; and,

FIG. 6 is a bottom plan view thereof.

The broken line showing of the wheel chair and I.V. pole in the FIGS. 1 through 4 is for illustrated purposes only and forms no part of the claimed design.
